US00D669451S

(12) **United States Design Patent**
Tappeiner et al.

(10) **Patent No.:** **US D669,451 S**
(45) **Date of Patent:** ** *Oct. 23, 2012

(54) **HEADPHONES**

(75) Inventors: **Marc Alan Tappeiner**, Santa Barbara, CA (US); **Eric Michael Bergman**, Santa Barbara, CA (US); **Frank Bleck**, Santa Barbara, CA (US)

(73) Assignee: **Signeo USA, LLC**, Lake Mary, FL (US)

(*) Notice: This patent is subject to a terminal disclaimer.

(**) Term: **14 Years**

(21) Appl. No.: **29/399,578**

(22) Filed: **Aug. 16, 2011**

(51) **LOC (9) Cl.** **14-01**

(52) **U.S. Cl.** **D14/205**

(58) **Field of Classification Search** D14/205, D14/206, 223; 181/129, 130, 135; 379/430, 379/431, 433.05; 381/370, 371, 374, 380, 381/381; 2/209, 423; D5/52, 53; 455/90.3, 455/575.2

See application file for complete search history.
